UNITED STATES PATENT OFFICE

FRITZ VAN DER WOUDE, OF ELYRIA, OHIO, ASSIGNOR TO THE GENERAL INDUSTRIES COMPANY, OF ELYRIA, OHIO, A CORPORATION OF OHIO

GOVERNOR

Application filed August 20, 1929, Serial No. 387,143. Renewed August 23, 1930.

My invention relates to centrifugal governors and relates more particularly to governors applicable to controlling the speed of such mechanisms as phonograph motors and 5 the like, employing either electric motor or spring motor power.

In motor mechanisms such as employed for driving a phonograph turntable, the maintenance of a predetermined rotational speed 10 is of importance, and centrifugal governors of various types have long been employed, and of these types the general type relying upon the effect of braking of a rotational motor part commensurably with the speed 15 at which said part is rotated, is most commonly employed.

An object of the present invention is to provide an improved centrifugal governor of a form adapted for disposition in a very narrow space extending in the direction of the 20 axis of the rotating part, such as a phonograph motor driven shaft.

Another object of my invention is to provide an improved centrifugal governor 25 adapted to effect a very graduated but heavy braking effect upon the motor shaft commensurably with increases of speed of such shaft.

Another object of my invention is to provide an improved mechanism of the class described adapted to be manufactured in quantities at small cost.

Another object of my invention is to provide an improved mechanism of the class described wherein adjustments of speed may be 35 readily effected with ease, and which adjustments will remain substantially permanent for long periods.

Other objects of my invention and the invention itself will become apparent from the 40 following description of an embodiment of my invention and in which description reference will be had to the accompanying drawings illustrating the said embodiment.

Referring to the drawings:

Fig. 1 illustrates, in side elevational view, 45 a centrifugal governor mechanism applied to a rotatable shaft of a motor whose speed is to be controlled thereby, a part of the enclosing casing being illustrated in longitudinal medial sectional view.

Fig. 2 is an end elevational view of the shaft carried parts of the centrifugal governor mechanism of Fig. 1.

Fig. 3 is a side elevational view of the shaft 55 carried parts of Fig. 1, shown in the relative positions assumed when the rotatable shaft is rotated at an operative speed.

Fig. 4 is a view like that of Fig. 2, but with the parts shown in the relative positions assumed under the conditions of operation existing for the view of Fig. 3.

Fig. 5 is a view like that of Fig. 4, but the view being taken at right angles to the view of Fig. 4.

Fig. 6 is an end elevational view of one of 65 two like complementary plates, the view showing an outer face of such plate.

Fig. 7 is an end elevational view illustrating the inner face of the plate of Fig. 6.

Fig. 8 is an end elevational view of the 70 plate of Figs. 6 and 7, showing the inner face of such plate.

Fig. 9 is a side elevational view of one of the plates shown in the foregoing figures, together with a supporting bushing projected 75 therethrough.

Fig. 10 is a view in side elevation of a resilient weighted centrifugal element acting as one of two like connectors for the pair of complementary plates of the said embodiment. 80

Referring to the figures of drawing in all of which like parts are designated by like reference characters, at 1 and 2 I show preferably like complementary plates, each with an enlarged central portion which is bored 85 axially to permit the plates to be telescoped on to the motor shaft 3.

The central portion of each plate is provided on one of its sides with a plurality of 90 preferably like spaced projections, each with a part helicoidal cam face. In the embodiment illustrated, each plate has three of such projections at 7, 8 and 9, disposed around the central axis of the plate, all equally spaced 95 radially of its aperture.

Axially disposed tubular bushings are 100 pressed into each plate perforation, and make a bearing contact with the shaft on to which it is fitted. However, a set screw 4, is screw threaded through the bushing 5, of the plate

1, and engages the shaft 3, to prevent relative rotational movement of the plate 1 on the shaft, with which it rotates.

The plates are so telescoped on to the shaft 5 that their inner faces are relatively disposed in opposition, and with the inwardly extending cam projections 7, 8 and 9 of each plate in engagement with like but oppositely extending cam projections of the other plate.

10 The two plates being made alike and turned in opposite directions, in position, the camming faces will be relatively so disposed for such camming interengagement as to effect gradual axial separation of the plates upon 15 relative rotational movement thereof.

Each of the plates is provided with a pair of oppositely outwardly extending arms 10 and 11, each of which is provided with an inwardly extending flange portion, shown re-

20 spectively at 10' and 11'.

As shown in Figs. 1 to 5 inclusive, the inwardly projecting flange portions of each plate are adapted to overlie the centrally disposed cam-carrying portion of the other 25 plate, and the pairs of arms of each plate are sufficiently displaced radially, relative to the arms of the other plate, so that the flanged arm ends thereof are adapted to be disposed side by side with the similarly flanged ends 30 of the arms of the other plate, which extend from a direction oppositely thereto.

With the plates both positioned on the shaft, as shown and described, they are resiliently joined together by a pair of steel 35 leaf springs 13 and 14, each of the springs having perforated ends through which screws 12 may be projected, and which are screw threaded into the flanges 10' and 11' of the plate arms 10 and 11. It will be understood, in this connection, that each of the 40 springs 13 and 14 is secured at its opposite ends to a flange 10' of the one plate and a flange 11' of the other plate, and which flanges are located on opposite sides of the 45 motor shaft 3.

Fig. 10 shows the preferred normal straight form of the spring 13 having its ends 50 perforated at 15 and 16 and carrying a weight 17 attached to its mid portion by a screw 18 projected through a central aperture of the spring and screw threaded into the weight 17.

Two of the centrifugal elements shown in Fig. 10 are employed, and are of such increased length relative to the maximum spacings normally existing between opposite arm flanges of two different ones of the plates 55 1 and 2, that when secured thereto by the screws 12, the springs 13 or 14, as the case may be, take the bowed form shown in Fig. 2.

At the same time, due to the resilient resistance of the spring to distortion from its straight form, a retractive pressure effort is exerted by each of the springs, tending to 60 relatively rotate the plates in such a direc-

tion as to bring the adjacent flanges 10' and 11' of each plate at opposite sides of the shaft, together, and to resiliently tend to maintain them in contact.

Separation of the arms 10 and 11, carrying 70 the flanges 10' and 11' by relative rotation of the plates 1 and 2, is effected only against the spring pressure of the centrifugal elements 13 and 14, causing the springs thereof to take a more severely bowed form, and with a corresponding increase in retractive resistance offered by the springs.

The flattened leaf springs 13 and 14 also resiliently resist axial displacement of the plates relative to each other tending to keep 80 them resiliently pressed together with the faces of their cams 7, 8 and 9 in resiliently maintained contact.

The two centrifugal elements are, therefore, mounted on the device on opposite sides 85 of the shaft 3, and when the shaft is rotated, driving of the plates is effected, the plate 1 communicating rotative movement to the plate 2 through the springs 13 and 14 of the 90 centrifugal elements.

As will be understood from the above description, the springs perform the function of maintaining a rotative pressure effort on the plates to press their arm flanges toward each other, tending to the ultimate positions 95 shown in Fig. 2. Also the springs resiliently exert a pressure effort tending to move the plates together in a direction axially of the shaft. The springs also communicate rotative movement from the plate 1 to the plate 100 2 when the plate 1 is rotated by the shaft.

In addition to the above functions for the spring 13, the spring 13 communicates a centrifugally effected pressure effort over the weights 17, which tend to be thrown outwardly from the shaft 3 upon rotation thereof, to the outwardly extending arms 10 and 11 of the plates. The springs, in performing such function, act as tractive links between the weights and oppositely positioned ends 110 of the two different plates 1 and 2.

The latter effect is exerted in opposition to the first three effects named, and at all speeds within the range of operation contemplated. The weights counter-balance the resilient effort exerted by the springs, tending to relatively rotate the plates toward the normal position of Fig. 2 and tend to separate the flanged ends of the arms 10 and 11 to such a separated position as is commensurable with the rate of rotation of the shaft. As the shaft rotates faster, the gap shown at *a* and *b* in Fig. 4, for the associated pairs of plate arms, becomes greater.

The plate 2 is provided with a smooth 125 annular friction surface, shown at 19, Figs. 1 and 2, and a braking friction pad 20 supported on a lever 21, pivoted at 22, to a projection 23 of the casing 24, is adapted for engagement therewith. The position of the 130

friction pad 20 longitudinally of the shaft 3, is adjustably predetermined by operation of the adjusting screw 25 screw threaded through a wall of the casing, and engaging at its end with the lever 21, which is spring pressed thereagainst through the action of a retractile compression spring 26 interposed between the opposite arm of the lever and a wall of the casing.

In addition to the arms 1 and 2 being variably spaced at *a* and *b*, radially of the shaft 3, because of the centrifugal effect of rotation of the weights 17 about the shaft, such separation of the arm ends is accompanied by a relative axial movement of the plates, since the cam projections 7, 8 and 9 of the two plates having their oppositely inclined faces in engagement, rotation of the shaft will effect relative camming between the projections to tend to separate the plates, this being resisted meanwhile by the resiliently distorted springs 13 and 14, which carry the weights and which interconnect the two plates.

The relative axial movement of the plates 1 and 2, therefore, moves the plate 2 outwardly on the shaft 3 and away from the other plate, and causes it to make increased pressure engagement by its annular friction surface 19 on the outer surface of the plate 2, with the friction pad 20 carried on the inner face of the adjustable lever 21.

The frictional engagement had between the pad 20 and the frictional braking surface 19 of the plate 2, effects a retardation in rotational speed of the plate 2, and which retardation is communicated to the shaft through the springs.

During operation of the device, the friction pad 20 is stationary in its adjusted position, and the plane annular surface 19 of the plate 2 is moved axially against the pad upon the increased speed, and the friction pad consequently engages it with increased pressure, retarding its rotative speed, whereupon the springs 13 and 14 resiliently retract the plate 2 to tend to withdraw it from contact with the pad.

All of these effects occur coincidentally, and the speed is maintained within very narrow limits at substantially a constant speed, even though there be, from time to time, variations in motor driving effect, or in the power required to drive the load, such as a phonograph turntable, since to compensate for such effects there will be opposite compensating variations in frictional retardation effected upon the plate 2, and thereby upon the shaft carrying the plate.

Having thus described my invention in a preferred embodiment, I am aware that numerous and extensive departures may be made from the embodiment herein illustrated and described, but without departing from the spirit of my invention. For example

while I have shown the plates 1 and 2 as composed of solid material it may be formed by drawing and pressing operations from a sheet metal, or may be otherwise produced from other materials or built up of a number of parts.

I claim:

1. In a speed governor, in combination with a rotatable shaft of a device to be governed, a pair of plates carried by the shaft, one of said plates being secured to the shaft, the other plate being adapted to float axially and rotationally within limits relative thereto, a resilient centrifugal element, portions of said plates, said plates having inner faces cooperatively formed for camming inter-engagement, whereby varying relative rotational movements of the plates will effect correspondingly varying relative movements of the plates axially of the shaft against the resilient effort of said centrifugal element, constantly tending to move said plate portions relatively rotationally and relatively axially closer together, and a friction element adapted for engagement with an axially movable outer surface of one of said plates.

2. In a speed governor, a pair of coaxially disposed plates, one carried by a shaft of a mechanism to be governed and rotatable thereby, means yieldingly resiliently joining the plates together, camming means operative to oppose the action of said resilient joining means, and an inertia element rotatable with one plate adapted to effect relative rotation of the plates, said camming means being thereupon adapted to vary the spacing of the plates longitudinally of the shaft according to the speed of the shaft, and shaft speed controlling means operatively responsive to the relative longitudinal movement of the plates.

3. In a speed governor, a pair of plates, one connected to a rotatable shaft of a device to be governed, means resiliently joining the plates to communicate rotary movement from the connected plate to the other plate, an inertia element connected to one of the plates and adapted upon increased speeds of the shaft to effect relative rotational movement of the plates, camming means interconnecting the plates adapted upon relative rotational movements thereof to relatively axially shift the plates, and friction means adapted to effect an increased retarding action upon the shaft upon relative axial movements of the plates.

4. In a speed governor, in combination with a rotatable shaft of a device to be governed, a pair of plates telescoped on to the shaft one being fixed thereto and receiving rotary movement therefrom, camming means interposed between the plates forming a contractual connection therebetween and adapted upon relative rotational movements of the plates in a given direction to move them relatively axially, means constantly operable

- tending to press the plates together, and a centrifugal element rotatable by the shaft variably operable according to the rotational speed thereof, adapted to effect a rotary shifting of one plate relative to the other plate, and a friction element engageable with said axially shifted plate upon a predetermined shifting thereof tending to retard the rotary movement thereof.
5. In a speed governor, in combination with a rotatable shaft of a device to be governed, a pair of plates telescoped on to the shaft one being fixed thereto and receiving rotary movement therefrom, camming means interposed between the plates forming a contactual connection therebetween, and adapted upon relative rotational movements of the plates in a given direction to move them axially, means constantly operable tending to press the plates together, and a centrifugal element rotatable by the shaft variably operable according to the rotational speed thereof, adapted to effect a rotary shifting of one plate relative to the other plate and a friction element engageable with said axially shifted plate upon a predetermined shifting thereof tending to retard the rotary movement thereof, and means to adjustably predetermine the relative position of said friction element relative to said shiftable plate to predetermine the governing effect thereof.
6. In a speed governor, in combination with a rotatable element of a device to be governed, a first governor element connected to the rotary element and rotatable therewith, a second governor element connected to the first governor element and adapted to be rotatably driven thereby, interengaging camming portions on the governor elements, a centrifugal inertia element rotatable with the governor elements and adapted at variable speeds to effect a camming action of one governor element on the other to variably move them relatively axially and friction means adapted to effect a retarding action upon the shaft upon relative axial movement of the governor elements.
7. In a speed governor, in combination with a rotatable element of a device to be governed, a first governor element connected to the rotary element and rotatable therewith, a second governor element connected to the first governor element adapted to be rotatably driven thereby and rotatably movable relatively thereto, interengaging camming portions on the governor elements, a centrifugal inertia element rotatable with the governor elements and adapted at variable speeds to relatively rotate the governor elements and thereby effect a camming action of one governor element on the other to variably move them relatively axially and friction means engageable by one of the governor elements upon relative axial movement thereof to effect a retarding action upon the shaft.
8. In a speed governor, in combination with a rotatable element of a device to be governed, a first governor element connected to the rotary element and rotatable therewith, a second governor element mounted for rotation relative to the first governor element, resilient means connecting the governor elements through which the second element may be rotatably driven by the first governor element, a centrifugal inertia element rotatable with the governor elements and adapted at variable speeds to effect relative rotational movement between the governor elements, interengaging camming portions on the governor elements effective upon relative rotation to move them relatively axially and friction means adapted to effect a retarding action upon the shaft upon relative axial movement of the governor elements.
9. In a speed governor, in combination with a rotatable element of a device to be governed, a first governor element connected to the rotary element and rotatable therewith, a second governor element mounted to rotate with the first governor element and mounted for rotational and axial movement relatively thereto, a resilient element connecting the two governor elements, a centrifugal inertia element on the resilient element and rotatable with the governor elements and adapted at variable speeds to effect relative rotation of the governor elements, interengaging camming portions on the governor elements adapted, upon relative movement, to effect relative axial movement of the governor elements and friction means adapted to effect a retarding action upon the rotatable element upon relative axial movement of the governor elements.
10. In a speed governor, in combination with a rotatable element of a device to be governed, a first plate connected to the rotary element for rotation therewith, a second plate mounted for rotary movement with the first plate and for rotary and axial movements relative to the first plate, a resilient element connecting the two plates and tending to hold the second plate in a predetermined normal relative position rotatably and axially, interengaging camming portions on the plates adapted, upon relative rotation of the second plate, to effect axial movement thereof, a centrifugal inertia element adapted at varying speeds to effect relatively rotary movement of the second plate, and friction means adapted to be engaged by a portion of the second plate to effect a braking action on the rotatable element responsive to relative axial movements of the second plate.
- In testimony whereof I hereunto affix my signature this 25th day of July, 1929.
- F. VAN DER WOUDE.
